UNITED STATES PATENT OFFICE.

JOHN J. FERRALL AND EDMUND MACKAY, OF NEW YORK, N. Y., ASSIGNEES TO
NATIONAL BISCUIT COMPANY, A CORPORATION OF NEW JERSEY.

BOX-SEAL.

940,242.

Specification of Letters Patent. Patented Nov. 16, 1909.

Application filed May 24, 1907. Serial No. 375,398.

To all whom it may concern:

Be it known that we, JOHN J. FERRALL and EDMUND MACKAY, citizens of the United States, residing at the city of New York, 5 borough of Manhattan, in the county and State of New York, have invented certain new and useful Improvements in Box-Seals, of which the following is a full, clear, and exact specification.

10 Our invention relates to means for sealing packages, containers or other receptacles, and the same has for its object more particularly to provide a simple, reliable and inexpensive device for effectually sealing 15 shipping packages.

Further, said invention has for its object to provide a sealing device which may be readily and quickly attached to a package, box or receptacle in such a manner that the 20 same cannot be opened to obtain access to its contents without destroying said sealing device, and rendering the same unfit for further use.

Further, said invention has for its object 25 to provide a sealing device for packages which is so constructed and arranged upon a package that a portion thereof shall be exposed and readily observable in order to indicate at once to a purchaser whether any 30 attempt has been made to reach the contents of said package.

Further, said invention has for its object to provide a sealing device for the purposes aforesaid which shall be simple and compact 35 in construction, and not interfere with the ordinary use of the package.

To the attainment of the aforesaid objects and ends our invention consists in the novel 40 details of construction, and in the combination, connection and arrangement of parts hereinafter more fully described, and then pointed out in the claims.

In the accompanying drawings, forming 45 part of this specification, wherein like numerals of reference indicate like parts, Figure 1 is a front view of a cracker box with a sealing device constructed and embodying our invention applied thereto; Fig. 2 is an 50 enlarged detail perspective of the sealing device ready to be applied to the receptacle; Fig. 3 is an enlarged face view of a portion of a cracker box with the sealing device applied; Fig. 4 is an enlarged detail section taken on the line 4—4 of Fig. 3; Fig. 5 is a 55 sectional view taken on the line 5—5 of Fig.

4, looking in the direction of the arrow, and Fig. 6 is a perspective view of the attaching member of the sealing device.

In said drawings 10 designates a metal cracker box or shipping package comprising 60 a box portion 11 open at its top, and provided with a hinged cover 12 having a depending rim or flange 13 which is adapted to extend over and inclose the upper edges of the box portion 11, as best shown at Fig. 4. 65

The front wall of the box portion 11 is provided near its upper edge midway between the side walls with an aperture into which is fitted from inside the outer or forward end of a tubular member or sleeve 14 70 which is provided with an annular rib or flange 15 adapted to bear against the inner side of the front wall of the box portion, and has its extreme outer end 16 turned over in order to clamp the material of the front wall 75 between said flange 15 and end 16. In the front depending part 13 of the cover 12 is provided an aperture 17 which registers with the opening of the tubular member or sleeve 14 when the cover 12 is closed down upon 80 the box portion 11.

18 denotes the sealing device comprising a spring member 19, and a head 20 secured thereto. The head 20 is preferably struck-up from a piece of sheet metal and is made 85 circular in outline and provided with a peripheral rim 21. The central portion of the head is partially severed therefrom to form two substantially semi-circular sections which are then bent rearward and toward 90 each other to form a round, integral, frangible section or ligament 22.

The spring member 19 is preferably formed of a single piece of metal of suitable resiliency and comprises two legs or prongs 95 23, 23 having a transverse loop or eye 24 arranged at the junction of said legs 23, 23 adapted to embrace the ligament 22 of the head 20, and the free ends of said legs separated and provided with laterally projecting 100 integral lugs 25, 25.

To seal the filled box it simply becomes necessary to take the sealing device as illustrated and assembled at Fig. 2, and compress the inner or free ends of the legs 23, 23 sufficiently to permit of the same being passed through the aperture 17, and into the tubular member or sleeve 14. Hereupon the device is pushed inward until the lugs 25, 25 at the inner ends of the legs 23, 23 pass be- 110

yond the inner end of the sleeve 14 when the same, owing to their resiliency will be caused to spread apart, and the lugs 23, 25 thereof engage the inner end of the tubular member or sleeve 14, and thereby secure the device in position and lock the cover securely to the box.

To open the box it is necessary to pry off or otherwise remove the head 20 from the attaching spring member 19, and this cannot be done without destroying the seal, since the attaching spring-member 19 cannot be separated from the head 20 without breaking the frangible ligament 22. As soon as the head 20 has been severed from the attaching-member 19, the latter may be pushed into the box and the cover thereof opened.

It will be obvious that as soon as the sealing device has once been broken the same cannot be again used owing to the ligament 22 being destroyed, and the head thereby rendered useless.

Having thus described our invention, what we claim and desire to secure by Letters Patent is:

1. The combination with a receptacle and cover, of a sealing device comprising a member having a frangible section thereon, and a resilient attaching member secured to said frangible section, said sealing device being adapted to engage said receptacle and cover, substantially as specified.

2. A sealing device for receptacles, comprising a head having an integral frangible section, and a separate resilient attaching member carried by the frangible section on said head, and adapted to engage said receptacle, substantially as specified.

3. A sealing device for receptacles, comprising a head having a central, integral, frangible section, and an attaching member secured intermediate its ends to said frangible section, and adapted to engage said receptacle, substantially as specified.

4. A sealing device for receptacles comprising a flat head having a central, integral, frangible section, and a resilient attaching member secured intermediate its ends to said frangible section, and adapted to engage said receptacle, substantially as specified.

5. A sealing device for receptacles, comprising a flat head having a central, integral, frangible section, and a resilient attaching member comprising a plurality of prongs provided at their free ends with engaging

means and secured at their connected ends to the frangible section of said head, substantially as specified.

6. The combination with a receptacle and a cover having an aperture therein, of a sealing device comprising a sleeve secured in said receptacle, in register with the aperture in said cover, a head having a frangible section, and an attaching member secured to said head and adapted to extend through said aperture and sleeve and held thereby, substantially as specified.

7. The combination with a receptacle and a cover having an aperture therein, of a sealing device comprising a sleeve secured in said receptacle in line with the aperture in said cover, a head having an integral, frangible section, and a resilient attaching member secured to said resilient section and adapted for securing in said aperture and sleeve, substantially as specified.

8. The combination with a receptacle and a cover having an aperture therein, of a sealing device comprising a sleeve secured at one end in said receptacle and in line with the aperture in said cover, a head having an integral frangible section, and a resilient attaching member comprising a plurality of prongs and secured to said frangible section at the junction of said prongs, and adapted to engage at their free ends with the inner end of said sleeve, substantially as specified.

9. The combination with a receptacle and cover having an aperture therein, of a sealing device comprising a sleeve having an annular flange adjacent to one of its ends and secured to said receptacle intermediate said flange and its adjacent end, a head having a central, integral, frangible section, and a resilient attaching member secured intermediate its ends to said frangible sections, and having a plurality of prongs adapted to extend through said sleeve and the aperture in said cover and provided at their free ends with projections adapted to engage the rear end of said sleeve, substantially as specified.

Signed at the city of New York, in the county and State of New York, this seventeenth day of May, nineteen hundred and seven.

JOHN J. FERRALL.
EDMUND MACKAY.
